MACHINES FOR REMOVING FINS FROM FINNED TUBES

Robert M. Stikeleather, Holbrook, Mass., assignor to Aerofin Corporation, Syracuse, N.Y.
Original application Dec. 23, 1958, Ser. No. 782,506.
Divided and this application Aug. 1, 1962, Ser. No. 213,966

3 Claims. (Cl. 90—15)

This invention relates to cutters for removing spirally wound fins from finned heat exchange tubes.

This application is a division of my copending application, Serial No. 782,506, filed Dec. 23, 1958, which discloses a system for cutting off lengths of finned tubing as it emerges from a finning machine, and preparing the cut-off lengths of tubing for assembly in a heat exchanger. The present application is for the cutting machine which removes fins from the tubing to provide space for tube supports.

Spirally wound fins are caused to adhere to the tubes on which they are wound by deforming the ribbons which form the fins to cause them to curl about and adhere to the tubes. Since in many cases the fins are not additionally attached to the tubes as by soldering, prior to this invention it has not been possible to remove a predetermined number of turns of a fin without unwinding, bending or otherwise damaging adjacent turns of the fin.

This invention provides a pair of rotary cutters which rotate in opposite directions on opposite sides of a finned tube, one cutter being off-set with respect to the other cutter so that their combined widths are equal to the space along the length of a finned tube from which the fin is to be removed. The turns of fin in that space are removed without any damage to the adjacent turns of the fin.

An object of this invention is to remove a predetermined number of turns of spirally wound fin from a finned tube without damaging adjacent turns of the fin.

This invention will now be described with reference to the annexed drawings, of which:

FIG. 1 is a plan view looking downwardly upon a fin cutting machine embodying this invention, a finned tube from which turns of a fin have been removed being shown;

FIG. 2 is an end view of the machine, the finned tube also being shown, and

FIG. 3 is a side view of the machine, showing in dashed lines, the cutters of the machine in fin cutting position on opposite sides of the finned tube.

A frame 10 has slidably supported thereon a base 11. The frame 10 has an upturned outer end 12 to which is attached an air cylinder 13. The base 11 has an upturned outer end 14 to which is attached piston rod 15 of the cylinder 13. An electric motor 18 is mounted on the base 11, and has a shaft 20 with a gear 19 thereon. The gear 19 is meshed with a gear 21 on a shaft 22 in a journal 23 on top of the motor 18. The shaft 20 has a pulley 25 attached thereto. The shaft 22 has a pulley 26 attached thereto. The base 11 has an upturned inner end 28 on which is supported journal 30 of shaft 31 of a lower cutter 32, and a journal 33 of shaft 34 of an upper cutter 35, the shafts 31 and 34 being vertically aligned. Pulleys 40 and 41 are attached to the shafts 31 and 34 respectively.

The cutters 32 and 35 are spaced apart a distance equal to the diameter of a tube 38 having a fin 39 thereon, and the inner edge of the cutter 35 is aligned with the outer edge of the cutter 32 so that the effective cutting surface is sum of the widths of the cutters. The cutters are a sort of a cross between millers and saws, having cutting teeth which are narrower than those of the usual miller, and wider than those of the usual saw.

2

A belt 43 engages the pulleys 25 and 40. Another belt 45 engages the pulleys 26 and 41.

Horizontally extending guides 50 and 51 are attached to the outer side of the base portion 28, and are spaced apart a distance equal to the outer diameter of the fin 39. The guides have diverging outer portions 52 and 53 which serve to locate a finned tube between the cutters when the latter are moved to fin cutting position as will be described later.

Operation

In operation, the motor 18 rotates the gears 19 and 21 in opposite directions, and the latter rotate through the pulleys 25 and 26, the belts 43 and 45 respectively, and the pulleys 40 and 41 respectively, the cutters 32 and 35 respectively, in opposite directions. A finned tube 38 having turns of a fin at an intermediate position to be removed, shown as removed by FIGS. 1 and 2, is supported in front of the machine as disclosed in detail in said application.

Compressed air from a source which is not shown, is supplied into the cylinder 13, and the piston rod 15 of the latter moves the base 11 and the cutter mechanism mounted thereon towards the finned tube 38 until the cutters 32 and 35 are on opposite sides of the tube as shown by the dashed lines of FIG. 3. The cutters remain in this position while the finned tube is rotated between them 360° in opposite directions as described in my said application, and the rotating cutters remove the desired number of turns of the fin.

When the cutting is completed, the cylinder 13 is operated to retract its piston rod 15 and the cutter assembly, leaving the tube with a bare intermediate portion as shown by FIGS. 1 and 2. The motor 18 is then deenergized until turns of a fin are to be removed from another tube.

Both cutters 32 and 35 rotate in the direction that the fin is spirally wound on the tube so as to prevent the fin from unwinding when the cutters are applied to it. Since the cutters are on opposite sides of the tube, this requires that they rotate in opposite directions.

What is claimed, is:

1. A machine for removing fin from a finned tube comprising a frame, an electric motor supported on said frame, a first gear and a first pulley on the shaft of said motor, a second gear meshed with said gear, a second shaft for said second gear, a journal supported on said frame for said second shaft, a second pulley on said second shaft, a first circular, rotary cutter, a third shaft for said cutter, a journal supported on said frame for said third shaft, a third pulley on said third shaft, a second rotary, circular cutter, a fourth shaft for said second cutter, a journal supported on said frame for said fourth shaft, a fourth pulley on said fourth shaft, said shafts having parallel axes, belts around said first and second and around said third and fourth pulleys, said cutters being spaced apart at their peripheral edges in a direction normal to said axes a distance equal to the diameter of a tube from which fin is to be removed, said cutters being displaced in the direction of said axes so that the inner edge of one of said cutters and the outer edge of the other one of said cutters extend substantially in a plane normal to said axes, and a pair of guides supported from said frame between said third and fourth shafts, said guides extending outwardly beyond said cutters and being spaced apart in a direction normal to said axes a distance equal substantially to the outer diameter of the fin on said tube.

2. A machine for removing fin from a finned tube comprising a frame, an electric motor supported on said frame, a first gear and a first pulley on the shaft of said motor, a second gear meshed with said gear, a second shaft for said second gear, a journal supported on said frame for said second shaft, a second pulley on said second shaft, a first circular, rotary cutter, a third shaft for said cutter, a journal supported on said frame for said third shaft, a third pulley on said third shaft, a second rotary, circular cutter, a fourth shaft for said second cutter, a journal supported on said frame for said fourth shaft, a fourth pulley on said fourth shaft, said shafts having parallel axes, belts around said first and second and around said third and fourth pulleys, said cutters being spaced apart at their peripheral edges in a direction normal to said axes a distance equal to the diameter of a tube from which fin is to be removed, said cutters being displaced in the direction of said axes so that the inner edge of one of said cutters and the outer edge of the other one of said cutters extend substantially in a plane normal to said axes, and a pair of guides supported from said frame between said third and fourth shafts, said guides extending outwardly beyond said cutters and being spaced apart in a direction normal to said axes a distance equal substantially to the outer diameter of the fin on said tube.

nal supported on said frame for said third shaft, a third pulley on said third shaft, a second rotary, circular cutter, a fourth shaft for said second cutter, a journal supported on said frame for said fourth shaft, a fourth pulley on said fourth shaft, said shafts having parallel axes, belts around said first and second and around said third and fourth pulleys, said cutters being spaced apart at their peripheral edges in a direction normal to said axes a distance equal to the diameter of a tube from which fin is to be removed, and a pair of guides supported from said frame between 10 said third and fourth shafts, said guides extending outwardly beyond said cutters and being spaced apart in a direction normal to said axes a distance equal substantially to the outer diameter of the fin on said tube.

3. The invention claimed in claim 2 in which said 15 motor, said journals and said guides are supported from said frame on a base that is slidable on said frame, and

in which means is provided for alternately moving said base forwardly from its normal position and returning said base to said position.
